CONDENSATE TRAP FOR SUCTION CONDUITS

Harry Campbell Grant, Jr., New York, N. Y., assignor to Walter Kidde & Company, Inc., Bloomfield, N. J., a corporation of New York

Application December 17, 1935, Serial No. 54,959

19 Claims. (Cl. 137—103)

This invention has reference to water traps adapted for use with systems and apparatus comprising tubes or pipes through which air or gas is continuously being drawn by suction.

5 The invention is particularly applicable to systems and apparatus used for the detection of fire in rooms and spaces which are removed from the place of detection or observation. It relates more particularly to the type of system 10 wherein pipes or tubes extend from the separate compartments or rooms to the point of observation, so that if fire breaks out in any one space or room, smoke will automatically be drawn or caused to flow to the observation place 15 and in this way the fact that a fire exists in any such space is made known, and accordingly appropriate steps may be taken.

Such fire detecting systems as applied particularly for marine usage have been disclosed in 20 patents to Freygang, No. 1,343,911, and others.

The object of this invention is to provide an improvement for such systems which overcomes certain disadvantages that have arisen in the past.

25 Apparatus of this type has been subject to one very serious objection in its use on ships or in buildings when the conduits connecting the rooms or compartments with the observation cabinet are subjected to a series of temperature 30 changes depending on the paths followed by the conduits in connecting the spaces to the cabinets.

As is well known the moisture content of the air in a given space may be varied by increasing or decreasing the temperature of the space. At 35 low temperatures the moisture saturation point of the air is considerably lower than the saturation point of the air at a higher temperature. Thus with a high temperature a given amount of air is capable of carrying a larger amount of 40 moisture than the same amount of air can carry at a lower temperature. Consequently, if a conduit drawing air, in which there is plenty of moisture, from a warm room passes through a very cold room on its way to the cabinet, some 45 of the moisture in the air will drop out as it passes through the colder region. The moisture becomes liquid and stays in the conduit, collecting at the lowest point in the conduit. When sufficient condensed liquid has collected, it will 50 either decrease the area of the conduit and thus the amount of air being drawn through the conduit, thereby decreasing the efficiency of the detecting system, or it will close the conduit to all passage of air, thus defeating the whole purpose 55 of the system.

It is accordingly an object of the present invention to provide a device which will remove any condensed liquid in the detector lines before it can prevent the detecting system from functioning at its highest efficiency.

It is a further object to provide a condensate remover which will operate automatically and will require no attention and will also permit a suction to be carried in the conduit at all times.

These objects, as well as additional objects and advantages will be best understood from the following description of a particular embodiment of the invention and by consideration of the accompanying drawing, the novel features of the invention being set forth with particularity in the appended claims.

In order that the invention may be better understood, attention is directed to the accompanying drawing in which Figure 1 is a vertical sectional view showing a section through the cabinet, one of the detector pipes throughout (except where the vertical and longitudinal legs thereof are broken away) and the upper ends of two other detector pipes leading into the cabinet of a fire indicating system in which the present invention has been applied. Figure 2 is a vertical sectional view showing the details of the device of the present invention as it is attached to a conduit of the fire indicating system. Figure 3 is an elevational view at right angles to Figure 2 of the device of the present invention. Figure 4 is a cross sectional view taken along line 4—4 of Figure 2.

A brief description of a fire detecting system with which the present invention is used is best 35 understood by reference to Figure 1. The detector cabinet is directly connected to the space which is to be supervised by a pipe or conduit 3 which leads directly into the chamber 5. The open ends of the detector pipes are disclosed 40 through the glass front 7. The ends are usually arranged in banks with the ends raised to different levels as can be seen by the various heights at which the ends 9, 11 and 13 of the detector lines are placed. The chamber 5 is illuminated by artificial means, such as an electric light bulb so that the presence of smoke issuing from any one of the detector lines may be readily ascertained. A rotary blower 15 is mounted in a suitable casing 17 above the chamber 5, and is operated by an electric motor 19. A pipe 21 connects the interior of the chamber 5 with suction of the blower, and the exhaust pipe 23 leads to the room in which the cabinet is located whereby all, or, if desired, a part only 55

of the air drawn through the detector pipes will be discharged into that room and the presence of any smoke will be detected by its odor.

The lower end of each detector pipe is preferably provided with a hood 25 in the compartment, made partly spherical, as shown, and through which air and smoke will be drawn into the detector pipe. Ordinarily the horizontal leg of each detector pipe with the hood 17 at its end will be located in the top of each compartment so as to be out of the way of its contents, but obviously the hoods may be located elsewhere.

It will accordingly be seen that in this system the blower 15 is continuously or intermittently operating, and will draw air through the several detector pipes from all the compartments to which they lead through chamber 5 where the escape of smoke from the end of any detector pipe may be observed through the glass 7 in the event fire has broken out in the compartment corresponding to that detector pipe.

In order to insure clear passage through the detector conduits in the event that liquid condenses out of the air passing through the pipes, each pipe is provided with one or more condensation traps at the low points in the pipes where liquid would ordinarily collect. One trap 27 is shown on pipe 3.

The trap 27 illustrated by Figure 2 consists of a main casing 29 of brass or bronze having a curved passage 31. The conduit 3 is provided with a hole 33 in which is placed a "Monel metal" sleeve 35 which extends through the pipe 35 and into the passage 31 where it rests on a seat 37. Surrounding the sleeve and resting between the conduit and the casing is a gasket 39 to insure an airtight connection between the casing and the conduit since it is imperative that no air enter the casing or the conduit during the operation of the apparatus. The passage 31 becomes horizontal and is met by the vertical passage 41. At the upper extremity of this passage is a seat 43. Surrounding the seat 43 is a chamber 45 which serves to keep the disc 47 from getting into such a position that it would not rest on the seat 43 when it falls or is pulled to rest on the seat. The disc must be made of a material which may be raised from its seat by the condensed liquid, be light enough to be drawn to the seat by a slight suction, be impervious to air, and make a joint with the seat through which no air can be drawn. A material which has been found to have the required properties and which will serve the purpose is that known as "Celeron" in the trade. Above the chamber 45 and communicating with it is another chamber 51 with a recess 53. Another washer 55 surrounding the opening of the chamber 45 lies in the recess 53. Resting on the washer 55 is an outlet casing 57 of brass or bronze, the upper portion of which rests securely against the conduit 3. This casing has a passage 59 of the same size and directly in line with the passage 41 of the main condensate trap casing. A seat 60 at the end of the passage 59 is also provided, the purpose of which will be explained hereinafter.

As will be noted the disc 47 is made of a diameter sufficient to prevent the disc from either going up into the passage 59 or down into the passage 41. The disc must therefore remain in the chamber 45 and no matter how the disc falls on the seat it will always close off the passage 41; the degree of tightness with which it rests on the seat, of course, depending on gravity and the

suction present in the pipe. The material, size and shape of the disc and the design of the chamber are such that any condensed liquid collecting in the trap and escaping therefrom cannot raise the disc to the seat 60 and so prevent the liquid from escaping. A very high pressure would, of course, push this disc against the seat 60 but the slight pressure exerted by the liquid head is insufficient to do this, being merely sufficient to raise the disc high enough off the seat 43 to permit the liquid to seep around the edges of the seat and escape through the discharge passages.

In the wall of this casing at right angles to the passage 59 are provided two square openings which are best illustrated by Figure 4. It is through these openings that any liquid collected in the conduit is permitted to escape.

The entire liquid trap consisting of the two casings 29 and 57 is securely held in communication with the hole 33 and the pipe 3 by the clamp 63. The casing 29 is provided with lugs 65 having holes through which the clamp 63 passes. The amount of pressure with which the trap rests against the pipe may be increased or decreased or the entire trap may be removed from the pipe by means of the nuts 67 which are in threaded engagement with the clamp 63.

If any liquid collects in the pipe 3 the liquid will naturally run to the lowest point and stand there. The hole 33 is accordingly made at such a low point and the trap attached. The liquid seeking a lower level will then flow into the trap. It will flow into the horizontal passage 31 where it will collect until enough liquid has been collected to raise the disc from its seat. As the amount of liquid increases the level will rise until it has reached the level of the square openings 61 when it will flow through these openings and escape. Since the disc is of a material that will not float, it will be carried in suspension in the liquid and will thus permit the liquid to flow by the seat 60 through the passage 59 and out of the trap.

When there is no condensed liquid in the trap, or when the amount of liquid is insufficient to close off the passage to the disc the suction which is present in the pipe is sufficient to hold the disc on its seat. When the passage has enough liquid to fill the passage but insufficient to raise the disc off its seat the liquid in the passage will serve to seal off the conduit from the air so that in this condition there is no necessity for the disc and seat. When the liquid is sufficient to raise the disc off its seat the liquid is free to flow through the square passages when the level of the liquid has risen to the level of these passages. Obviously the amount of suction which is present in the pipe will control the size of the condensate trap. The trap as shown is designed for a suction of about an inch of water or less but it is possible to use this trap when the suction is greater. When the trap is used for a higher suction it is necessary to periodically shut off the suction in the conduit so that any condensed liquid will be permitted to flow through the trap and escape. As long as a high suction is present in the conduit it will hold the liquid in the conduit and trap and the liquid cannot escape, but releasing the suction permits the liquid to escape under its own head. However, if it is desired to make a trap which will operate at greater vacuum and permit a continuous suction in the conduit, it is only necessary to make the passage 41 longer and to design the passage 31 in accordance.

The purpose of the seat 60 will now be ex-

plained. In some installations of fire detecting systems, it has been found to be of advantage to introduce, upon the discovery of fire in a space, a fire extinguishing medium, such as carbon dioxide under pressure, or high pressure steam, to that space by means of the detecting conduit. The extinguishing medium may be introduced through the ends of the conduit, as at 11, or a special valve may be installed on the conduit 3 which is not illustrated here but is shown in the Freygang Patent No. 1,343,911 previously referred to. When such a high pressure fire extinguishing medium is introduced into the conduit the pressure is so great that when the medium enters a trap it will force the disc 47 up against the seat 60 and press it there so tightly that none of the medium can escape from the trap. Therefore, it will be seen that the disc serves another purpose in that it prevents any high pressure medium introduced into a conduit from escaping through the trap. Another feature of this arrangement is that in the event any foreign material collects in the conduit compressed air may be introduced through the open end of the conduit and the undesired element blown out of the conduit without losing the air, and consequently pressure, through the trap.

It will thus be seen that a trap for a conduit under suction has been provided which will maintain the suction in the conduit by maintaining an air closed connection but which will automatically open when condensed liquid has collected in the conduit and permit the liquid to escape and thus preserve a clear passage through the conduit at all times.

Although the invention has been particularly shown and described in conjunction with a fire indicating system, the invention is not to be limited to fire indicating systems but is to be applied wherever a line is under suction.

Having now fully described my invention, what I claim is:—

1. A combined trap and outlet drain for the condensation products of a conduit normally under suction comprising a trap proper apart from the conduit, means to conduct the condensation products to the trap, means to effect communication of the trap with the atmosphere, and means preventing such communication when the conduit contains a high pressure fluid medium, said last named means being adapted to prevent atmospheric air from entering the trap.

2. A trap for liquid condensed in a conduit under suction comprising a casing having a passage, a sleeve in the passage extending into and communicating with the bore of the conduit, a gasket surrounding the sleeve and lying between the casing and the conduit, a chamber in the casing associated with the passage, a seat in the chamber, a disc normally resting on the seat, a recess in the casing associated with the chamber, a gasket in the recess, a second casing resting on the gasket and bearing against the conduit, a passage in the second casing communicating with the chamber, and outlets connecting the last named passage to the atmosphere.

3. In a condensate trap for a conduit normally under suction, means apart from the conduit to collect the condensation products, means connecting the conduit with the collecting means, means to permit flow of the condensation products from the trap, and means in the collecting means to prevent flow of air through the collecting means to the conduit, said last named

means being adapted to prevent the escape of any high pressure fluid medium introduced into the conduit.

4. In a water trap for a conduit normally under a partial vacuum, means apart from the conduit to collect any water condensed, means to drain away the condensed water, and means preventing entrance of air to the trap, said last named means being adapted to prevent the escape of any high pressure fluid medium introduced into the conduit.

5. In a trap for conduits normally under suction, means apart from the conduit to drain and collect liquid from a conduit, means to permit escape of the liquid, means preventing atmospheric air from entering the trap, said last named means being adapted to prevent escape of any high pressure fluid medium introduced into the conduit.

6. In a fire detecting and extinguishing system comprising a series of conduits connecting the spaces to be protected to a central observation chamber and having means to draw the air from the spaces to the chamber and means to introduce a fire extinguishing medium under pressure into the conduit, means to remove liquid condensation products from the conduits comprising means to drain and collect the condensation products, means to permit escape of the products, means to prevent the escape of the fire extinguishing medium under pressure from the conduits, and means to normally prevent air from entering the conduit through the removing means.

7. A trap for conduits normally under suction, comprising a casing apart from the conduit having a passage therethrough, a seat in the casing surrounding the passage, a disc maintained on the seat by the suction, a casing having a passage vented to the atmosphere, and a seat in the last named casing surrounding its passage, said disc normally preventing communication with the atmosphere and adapted to engage the second named seat when high pressure fluid is introduced in the conduit.

8. A trap for conduits normally under suction comprising a casing apart from the conduit to collect condensation products, means to permit the products to escape, and means to prevent entrance of air through the casing to the conduit but permitting escape of the products, said last named means being adapted to prevent the escape of any high pressure fluid medium introduced into the conduit.

9. In a condensation trap for a conduit normally subjected to suction, means apart from the conduit to drain the condensate from the conduit, means to remove the condensate from said means, and means to prevent the first said means from venting to the atmosphere when a high pressure fluid medium is introduced in the conduit, said last named means being adapted to prevent atmospheric air from entering the trap.

10. In a condensate trap for a conduit subjected to suction, a collecting casing associated with the conduit but apart therefrom, an atmospheric casing associated with the first casing, a seat in the first casing, a disc on the seat normally preventing communication with the atmosphere, and a seat in the atmospheric casing, said disc and said last named seat preventing leakage of any high pressure fluid medium introduced into the conduit.

11. In a trap for a suction conduit, a collecting

tion casing apart from the conduit, a sleeve joining the conduit and the casing, a chamber in the casing, a seat in the chamber, a disc normally on said seat, and a second casing associated with the chamber of the first casing, said second casing venting to the atmosphere.

12. In a trap for a suction conduit, a collection casing, a sleeve joining the conduit and casing, a gasket between the conduit and casing and surrounding the sleeve, a chamber in the casing, a seat in the chamber, a disc on the seat, a recess in the casing adjacent the chamber, a gasket in the recess, a second casing resting on the gasket and bearing on the conduit, an atmospheric vent in the second casing, lugs on the first casing, a clamp passing through the lugs and securing the whole to the conduit in airtight relationship.

13. In a condensate drain for a suction conduit, means to permit escape of the condensate and means to normally prevent communication with the atmosphere, said last named means being adapted to prevent the escape of any high pressure fluid medium introduced in the conduit.

14. In a condensate trap for a suction conduit, a collecting casing apart from the conduit, a chamber in the casing, a seat in the chamber, a disc on the seat, a recess in the casing adjacent the chamber, a gasket in the recess, a second casing associated with the first, and an atmospheric vent in the second casing.

15. In a liquid trap for a suction conduit, a liquid collecting casing apart from the conduit, a seat in the casing, a disc on the seat, a second casing associated with the first, and atmospheric vents in the second casing, said disc being raised from its seat by the drained liquid to permit the escape thereof through the atmospheric vents.

16. In a condensate trap for a suction conduit, a condensate collecting casing apart from the

conduit, means communicating with the atmosphere, and means to normally prevent communication between the conduit and the atmosphere, said last named means being operable to permit the condensate to escape through the means communicating with the atmosphere and to prevent the escape of any high pressure fluid medium introduced in the conduit.

17. In a trap for a suction conduit, collecting means apart from the conduit, a pair of valve seats in the collecting means, valve means between said pair of seats adapted to be seated in one direction by suction in the conduit and in the opposite direction by pressure in the conduit, and means vented to the atmosphere associated with the collecting means.

18. In a fluid trap for a suction conduit, means apart from the conduit to collect the fluid, means vented in the atmosphere to permit the fluid to flow off, and valve means preventing entrance of atmospheric air to the collecting means and preventing the escape of any high pressure fluid medium introduced in the conduit.

19. In a trap for a suction conduit, a collector casing, a sleeve connecting the conduit and the casing, a gasket surrounding the sleeve between the conduit and the casing, a chamber in the casing, a seat in the chamber, a disc on the seat, a recess in the casing adjacent the chamber, a gasket in the recess, a second casing resting on the gasket and bearing on the conduit, a seat on the second casing, said disc being adapted to rest on the last named seat when the conduit contains a high pressure fluid medium, an atmospheric vent in the second casing, lugs on the first casing, a clamp passing through the lugs and securing the trap to the conduit in airtight relationship.
